UNITED STATES PATENT OFFICE.

ALEXANDER WALKER, OF WALLSEND-UPON-TYNE, ENGLAND, ASSIGNOR OF ONE-HALF TO DRAKES LIMITED, OF OVENDEN, HALIFAX, ENGLAND.

MECHANISM FOR SCREENING OR SIFTING GRANULATED SUBSTANCES.

1,389,231.

Specification of Letters Patent. Patented Aug. 30, 1921.

Application filed March 30, 1915, Serial No. 18,174. Renewed January 31, 1921. Serial No. 441,502.

To all whom it may concern:

Be it known that I, ALEXANDER WALKER, a subject of the King of Great Britain, and residing at "Donwal," Kings Road, Wallsend-on-Tyne, in the county of Northumberland, England, have invented certain new and useful Improvements in Mechanism for Screening or Sifting Granulated Substances, of which the following description, having reference to the annexed sheets of drawings, is a specification.

In the screening or sifting of coke, coal, crushed stone and other granulated substances it is often desirable that the particles of matter should have imparted to them a rolling movement in order that other and smaller particles adhering to one side or the other of same may be thrown off. In apparatus wherein rotary sieves or screens as heretofore constructed are employed it is found that said rolling and other motions are so violent as to considerably damage or break up the substances being treated and especially is that the case in the screening or sifting of coke. In other forms of screens where longitudinal bars of a step like character have been used the effect we desire has not been attained since said bars have had interstices or spaces adjoining them throughout the length of the screen; or have had screening surfaces adjoining them produced by perforations being made through flat base plates none of which formations permit the rolling and other motions of the substances being treated that I secure by my devices.

The object of my invention is to obviate these disadvantages and produce apparatus that will carry out the actions desired and these I secure by forming my screening surfaces, consisting of series of projections or fingers with plain or blank parts intervening between them, in such manner that same do not in any way impair or deteriorate the substances being treated but which permit such substances to travel over them with the rolling and other motions described, while the extent to which said motions are imparted to said substances may be regulated to be increased or decreased as may be found necessary.

In carrying my invention into effect I make use of apparatus or mechanism as

illustrated by the accompanying sheets of drawings, wherein:

Fig. 1 is a side sectional elevation (taken on line C—D of Fig. 2) of a sieve and its hopper or chute constructed in accordance with my said invention.

Fig. 2 is a plan of the parts shown by Fig. 1.

Fig. 3 is a side sectional elevation of a sieve or screen of the reciprocating type.

Fig. 4 is a plan of the parts shown by Fig. 3.

Fig. 5 is a side elevation of a revolving screen.

Fig. 6 is an end elevation of said screen showing the operating shaft in section.

Figs. 7 and 8 are sectional elevation and plan drawn to an enlarged scale showing in detail the method of constructing my improved screen with, what may be termed, stationary screening devices.

Figs. 9 and 10 are sectional side elevation and plan showing how certain of my improved parts may be adjusted.

Fig. 11 is a drawing in detail hereinafter described.

Fig. 12 shows a portion of the mechanism illustrated by Fig. 5 but of a modified construction hereinafter described.

To attain the object of my invention, according to one arrangement I make use of appropriate framework A upon which I may mount an inclined sieve or screen formed with blank parts a and open parts a^2 while at the outer edges of these are the sides a^1 which guide the substances over said screen as they descend from the hopper b into which they fall and from which they escape as will be understood. Thus on the granulated substances which have to be screened being placed in the receptacle b when the door or cover c is raised as shown by Fig. 1, said granulated substances will descend and spread over the whole surface of the screen as they travel over same. The screening surface is formed by having spaces a^2 to alternate between the blank parts or base plates a (said spaces and plates being of appropriate width) while overhanging those spaces a^2 and at an angle to the base plates a of the screen I have projections or fingers d .

The outer ends of these fingers d , as shown by Figs. 2 and 8 at d^1 , are narrower than are

their bases at d^2 , thus the slots e between them are broader at their outer than they are at their inner ends, by which formation when the granulated substances are traveling or 5 rolling over the blank parts a on encountering the fingers d the smaller particles will pass between said fingers while the larger particles will roll over and descend beyond same on to the succeeding portion of the 10 screen's blank parts a . In this manner said larger particles get rid of or discharge the smaller particles by these latter falling or passing through the openings e to descend to the ground or floor beneath, while the taper 15 formation of the fingers prevents the wedging of any particles between them by reason of the force of succeeding particles acting thereon causing them to travel forward. All the spaces a^2 which lie directly above the 20 base of the apparatus or within the uprights A permit the particles to fall perpendicularly while those of the spaces a^2 which are approaching the outer end a^3 of the screen will conduct the particles passing through 25 them on to the return chute f , thus the small particles or screenings will all be conducted into the space between the uprights A , while the particles that have been separated from said screenings will pass beyond the outer 30 end a^3 of the screen.

The same arrangement and formation of fingers d with intervening blank parts a may be followed in producing and making use of a screen that has reciprocatory motion transmitted to it, thus the screen illustrated by 35 Figs. 3 and 4 is mounted upon the pendent connecting rods g which are supported from the framework B , while reciprocatory motion is transmitted to said swinging screen or 40 sieve from the rotary shaft h upon which is fixed the eccentric h^1 , by said eccentric operating the sieve a by means of its connecting rod h^2 .

The granulated substances to be treated 45 are supplied to the sieve down the chute k .

Instead of the fingers d being fixed to the base or blank parts a of the screen they may be mounted upon pivots as d^3 , shown by 50 Figs. 9 and 10, so that by loosening the fixing bolt m which takes through the quadrant slot m^1 in the fixed bracket m^2 the fingers d may be adjusted at any angle relatively with the base a and when so adjusted may be secured by the bolt m being firmly screwed or 55 tightened up.

The base of the screen and the side walls thereof as well as the finger pieces may be of any appropriate kind of metal, as steel or the like or the finger pieces d may be of cast 60 metal or of other formation as may be found advantageous.

Leading to the screens hereinbefore described are the hopper b and chute k respectively and the orifices or openings p through 65 which the granulated substances have to pass

when leaving said chutes, are considerably narrower than the width of the screens as shown by Figs. 2 and 4 of the drawings, by which arrangement, as the granulated substances descend down the chutes in considerable thickness on escaping therefrom on to the base of the screen they separate or spread laterally to cover the whole surface or width of said screen and are thus more effectively treated thereby. 75

I have hereinbefore described my invention as for use in connection with flat inclined surfaces but I can also apply my improved formation of screening devices to cylindrical screens of the character illustrated by 80 Figs. 5, 6 and 12. Here the screen is mounted upon a shaft q to which motion is transmitted through gearing wheels r and r^1 from a main or other driving shaft s .

The bases p^1 upon which fingers d are 85 formed or fixed or from which they extend, form the base of the screen and the actions of the fingers d are in this case similar to the actions of the fingers d in the former constructions. According to one arrangement 90 I have made the fingers d to extend at right angles from the edges of the bases p^1 , as shown by Fig. 5, while according to another arrangement they extend, as shown in Fig. 12 at such an angle thereto as will cause them 95 to point or extend in the opposite direction to the rotations of the cylindrical screen as shown by Fig. 12.

The supplying of the granulated substances to the rotary screen is effected 100 through the chute t .

Although I have illustrated and described the projections d as extending from the base parts a so as to have free outer ends d^1 it is obvious that such projecting parts may be 105 made to extend from one base part a to the next below as shown by Fig. 11, and that they may or may not be fixed or secured to said adjoining base part.

Such being the nature and object of my 110 said invention what I claim is:—

1. Mechanism for cleaning and sifting granulated substances comprising a screen formed with alternating bottom portions and openings, each opening extending transversely of the screen, said bottom portions being inclined and lying in the same plane, a plurality of screening fingers on one edge of each bottom portion, said fingers being upwardly inclined relatively to the bottom portion and projecting in the direction of travel of the said substances with their free ends overhanging the adjacent bottom portion beyond the opposing edge thereof, each bottom portion extending for a considerable distance from the finger overlapped edge thereof to its opposite edge, for providing extended flooring sections. 120

2. Mechanism for cleaning and sifting granulated substances, a screen element in- 130

cluding bottom sections with intervening adjustably mounted projections or fingers, and operable means for actuating and maintaining said projections or fingers at any desired 5 angle relative to said bottom sections of screen.

3. In mechanism for screening or sifting granulated substances, a screen for screening or sifting operations, a plurality of series 10 of teeth extending at an angle from the surface of said screen, blank parts intervening between said series of teeth, and means for adjustably varying the angles of the teeth of each series simultaneously.

15 4. In mechanism for screening or sifting

granulated substances, a screen for screening or sifting operations pivotally adjustable teeth extending from the surface of said screen, blank parts intervening between said teeth, an operable means for actuating and 20 maintaining said teeth at any desired angle relative to said blank parts forming the bottom of the screen.

In testimony whereof I have signed my name to this specification in the presence of 25 two subscribing witnesses.

ALEXANDER WALKER.
